(57) **CLAIM**

The ornamental design for a waterfowl (duck/goose) call shaped handle for an umbrella, as shown and described.

DESCRIPTION

FIG. 1 is a perspective view of a waterfowl (duck/goose) call shaped handle for an umbrella showing my new design;

FIG. 2 is a front view thereof;

FIG. 3 is a top view thereof; and,

FIG. 4 is a bottom view thereof.

The broken line showing in FIG. 4 is for illustrative purposes only and forms no part of the claimed design.
